CLAIM

The ornamental design for a vehicle fender, as shown and described.

DESCRIPTION

FIG. 1 is a front and left perspective view of the vehicle fender according to the present disclosure;

FIG. 2 is a top plan view thereof;

FIG. 3 is a front elevation view thereof; and,

FIG. 4 is a left end elevation view thereof.

The second embodiment of the vehicle fender is a mirror image of the first embodiment disclosed in FIGS. 1 through 4 and is not shown.

The broken lines shown in the drawings depict portions of the vehicle fender that form no part of the claimed design. The shade lines in the figures show contour and not surface ornamentation.
